METHOD AND APPARATUS FOR HANDLING

TRACK TIES

Virgil E. Glesup, 241 Division, Melrose Park, Ill., and
Russell E. Paulson, 406 N. Maple Ave., Itasca, Ill.
Filed Aug. 19, 1960, Ser. No. 50,799
16 Claims. (Cl. 214—520)

Our invention relates to the handling of railroad track ties, and more particularly, to the handling of new ties prior to their application to a railroad bed.

New track ties are creosoted after they have sufficiently dried and the creosoting is done by binding the ties into bundles of sufficient size to just fit into the creosoting tank, and after the bundles are placed in the tank, they are soaked in boiling creosoting oil for the prescribed period. After the creosoting process has been completed, they are delivered to the purchasing railroad by loading them into railroad cars sent to the creosoting plant for that purpose.

Experience has shown that the loading and unloading of the ties necessary to transport them to the point of use excessively aggrandizes the cost of new ties. This is caused by the necessary bulk of the individual ties and the handling problems peculiar to the different types of cars that are employed to transport the ties. In the past, boxcars and flatcars have been used to some extent as they minimize the amount that the ties have to be lifted, but the bulky nature of ties make boxcars difficult to load and ties are too apt to be dislodged from flatcars during transit. Gondola cars provide a satisfactory way of carrying the ties, but they require that the ties be lifted over the sides of the car both for loading and unloading.

Some efforts have been made to avoid the disadvantages of using standard car types for this purpose by the development of special cars and equipment involving a car specifically designed to facilitate loading and unloading of the ties, and a tie handling machine which is permanently associated with the car. One such development relates to a gondola-like car provided with removable sides and a tie kick-out type unloading device forming a permanent part of the car.

However, since on the order of 200 cars suitable for handling ties are required by any railroad having a moderate amount of trackage, and the individual special cars and their tie handling devices represent a substantial capital investment, this approach has not been given much serious consideration by the railroads.

Present practices in this art call for the use of standard gondola cars to carry the ties. The railroad purchasing ties sends its cars to the creosoting plant where the cars are loaded with ties in accordance with one of the standard loading procedures that have been approved for this purpose. Such procedures usually call for the ties being applied to the car in various crisscross patterns, with some of the ties standing vertically, for instance, along the sides and ends of the car; furthermore, steel strapping or the like is applied in various ways to keep the ties from shifting during transit. This necessarily means that much of the loading must be done by hand, even though suitable equipment may be available to lift the ties over the sides of the car. And at the unloading point, of course, much of the unloading must be done by hand.

These special handling requirements necessarily mean that labor and handling costs represent a sizable portion of the expense of new track ties.

A principal object of this invention is to provide a method and apparatus for handling track ties which permits the ties to be loaded into gondola cars in the bundled form that they are in when removed from the creosoting tank, and which provides a single tie unloading machine

2

that may be used to unload all the tie carrying cars in any particular train.

A further important object of this invention is to provide a method and apparatus for handling track ties which permits the use of existing rail equipment to the fullest extent possible.

Still further important objects of the invention are to provide a simplified and economical method of loading track ties into gondola cars, to provide apparatus for efficiently unloading the ties along the side of the track at a convenient distance from the track center line, and which may be readily moved from car to car at the unloading site, to provide a system of handling track ties involving the use of standard gondola cars and a tie unloading apparatus that rides on the tops of the sides of the cars, and to provide a machine for unloading track ties from a gondola car that is inexpensive of manufacture, convenient in use, and readily adapted for use on standard gondola cars without any modification of the latter and regardless of the age or condition of the car.

Other objects, uses and advantages will be obvious or become apparent from a consideration of the following detailed description and the application drawings.

In the drawings:

FIGURE 1 is a side elevational view of one end of a gondola car showing one embodiment of our tie unloading machine applied thereto in the process of unloading track ties therefrom;

FIGURE 2 is a small scale side elevational view of a train of three gondola cars, showing our tie unloading machine as mounted on one of the cars for tie unloading purposes;

FIGURE 3 is a plan view of a typical gondola car illustrating the manner in which the ties are loaded in the car in accordance with our invention;

FIGURE 3a is a diagram illustrating a typical tie bundle as it comes from the creosoting tanks;

FIGURE 4 is a fragmental side elevational view of the fork lift frame and associated structures of the tie unloader machine shown in the embodiment of FIGURE 1, parts being broken away to facilitate illustration;

FIGURE 5 is a plan view of the tie unloading machine of FIGURE 1, parts being broken away to facilitate illustration, and with the car being shown in broken lines;

FIGURE 6 is a fragmental sectional view substantially along line 6—6 of FIGURE 5, illustrating the tie ejector blade of our machine and the actuating device therefor;

FIGURE 7 is similar to FIGURE 6, but along line 7—7 of FIGURE 5;

FIGURE 8 is a diagrammatic cross-sectional view along line 8—8 of FIGURE 5;

FIGURE 9 is a cross-sectional view substantially along line 9—9 of FIGURE 5;

FIGURE 10 is a fragmental elevational view substantially along line 10—10 of FIGURE 5;

FIGURE 11 is an elevational view of one of the fork lift tie carrier frames forming a part of our tie unloading machine, as it would be viewed substantially along line 11—11 of FIGURE 5;

FIGURE 12 is a cross-sectional view substantially along line 12—12 of FIGURE 11;

FIGURE 13 is a plan view substantially along line 13—13 of FIGURE 11;

FIGURE 14 is a cross-sectional view substantially along line 14—14 of FIGURE 11;

FIGURE 15 is a cross-sectional view substantially along line 15—15 of FIGURE 11;

FIGURE 16 is a cross-sectional view substantially along line 16—16 of FIGURE 11;

FIGURE 17 is a cross-sectional view substantially along line 17—17 of FIGURE 4; and

FIGURES 18 and 19 are diagrammatic views illustrating the operation of the fork lift tines of our tie unloader in positioning same between their load carrying positions and their retracted positions for insertion underneath the ties to be unloaded.

GENERAL DESCRIPTION

Referring now to FIGURES 1, 2 and 3, our invention contemplates the use of conventional gondola cars 10 in which the individual track ties 12 are loaded in accordance with our method at the creosoting plant for transport to an unloading site where they are to be installed in the track bed, and a tie unloading apparatus or machine 14 that is employed for purposes of unloading the ties from the cars 10.

In accordance with our invention, the cars 10 are individually loaded with the ties 12 by initially forming two rows 16 (see FIGURE 3) of such ties laid end to end on the floor 18 of the car, which rows end in abutting relation with spaced spacer members 12a at the ends of the car that are formed from extra ties that are vertically disposed adjacent to that of the tie rows 16; the ties forming members 12a are shortened so as not to project above the top of gondola car sides.

The ties 12 are then loaded into the car 10 in any convenient manner and all such ties are oriented to extend transversely of the car. The ties 12 may be separated from the bundles in which they are creosoted and then loaded into car 3 by a suitable fork lift truck or overhead crane, or the tie bundles in the form they come from the creosoting tanks may be loaded directly into the car between the spaced vertically disposed members 12a by the aforementioned fork lift truck or overhead crane or other suitable grasping and elevating mechanism. The simplified showing of FIGURE 3 is intended to represent a typical car load of bundled ties (it is obvious how unbundled ties would appear in plan in a car 10 so this loading arrangement is not specifically illustrated), while FIGURE 3a is a representation of a typical tie bundle 13 per se, in which thirty-four ties 12 are bound together by steel strapping 15 in any conventional manner.

Of course, the ties are loaded into the car to a height commensurate with safe loading practices considering the height of the gondola side walls 22.

The cars 10 are then transported to the tie unloading site, and this is customarily done by connecting a number of cars 10 in a train, which train would also include a gondola car 10a (see FIGURE 2) on which the tie unloading apparatus or machine 14 is secured as by employing suitable tie down devices. Car 10a should be the last car in any train of gondola cars 10, and only about one half of the car (the left hand half in the showing of FIGURE 2) is loaded with ties, with the machine 14 being secured over the empty portion of the car (tie rows 16 and spacer members 12a being employed in the loaded end of car 10a in the manner already described).

The unloading site to which cars 10 are transferred ordinarily is an area of the track which is being improved as by replacing existing track ties, and the ties to be replaced customarily will have been previously marked. After the train of cars 10 and 10a have been brought to the beginning of the trackage where the existing ties are to be removed, the tie down devices anchoring tie unloading machine 14 in place are removed and the machine readied for use.

The tie unloading machine 14 generally comprises a wheeled frame 30 (see FIGURES 1 and 5) provided with double flanged wheels 32 and 32a that are thus formed to laterally confine frame 30 in its movements on top of the car side walls 22.

The wheeled frame 30 at its forward end swingably carries a fork lift frame 34, which is movable between

the full and broken line positions of FIGURE 1 and which defines spaced guideways 36 for tine carrying frames 38 that each pivotally mount a tine or prong member 40 mounted for swinging movement between the two positions indicated by FIGURES 18 and 19. The fork lift frame also has associated therewith a tie ejector device 42 which is mounted on machine 14 at a level that will be above the tops of the car side walls 22 (see FIGURE 1), when the machine is in operative position on the cars, and includes a reciprocably mounted paddle member or ejector blade 44, which is mounted for reciprocating movement over a distance corresponding to but somewhat greater than the distance between the sides of a car 10 (see FIGURE 5).

In the illustrated embodiment, the fork lift frame 34 may be pivoted or swung with respect to the wheeled frame 30 by appropriately operating a hydraulic multi telescoping cylinder or ram 50 interposed between the frame 34 and the wheeled frame somewhat as indicated in the drawings. The tine carrier frames 38 are reciprocated vertically in their guideways 36 by appropriate hydraulic cylinders 52 mounted within the respective guideways 36 and connected to the respective tine carrier frames. The tine carrier frames each carry an appropriate hydraulic cylinder 54 for moving the tines between the positions already mentioned.

The illustrated unloading device 14 also includes a rake device 56, including an extensible rake member 57, for drawing individual ties toward the tie ejector device after they have been elevated by the unloader machine, a pair of hydraulically operated clamping devices 58 (see FIGURE 9) for clamping the machine to the car during operation of the fork lift structure, a suitable braking arrangement such as that generally indicated at 60 in FIGURE 1, and a tie ejection movement control device 62 (see FIGURES 8 and 10) carried by each side of the fork lift frame 34 (see FIGURE 8). It is also contemplated that the machine 14 will be provided with a suitable operator's seat 64 (see FIGURE 5), a power unit such as a gasoline engine indicated at 66 but only diagrammatically illustrated, a suitable pump 68 (see FIGURE 5) operated by motor 66 for drawing hydraulic liquid from an appropriate reservoir 70 and supplying it to hydraulic motor 72 for purposes of moving the car along the tops of the side walls of cars 10 (as well as the hydraulic cylinder herein described), and suitable conduiting and valving for selectively supplying hydraulic liquid to the individual rams indicated, all of which may be done in a more or less conventional manner.

After the machine 14 has been released from its tie down devices, its internal combustion engine 66 is started and it is moved as required (by employing hydraulic motor 72) to first unload any ties carried by car 10a. After roughly properly positioning the machine with respect to the ties of car 10a to be unloaded, ram 50 is actuated to swing the fork lift frame 34 from its horizontal inoperative position to its vertical operative position of FIGURE 1; also, rams 52 are operated to fully extend tine carrier frame 38 to the lower broken line position of FIGURE 1 and tine carrier rams 54 are operated to move the tine members 40 from the broken line position of FIGURE 17 to the full line position of the same figure. This disposes tine members 40 between tie rows 16 of car 10a and below the level of the ties 12 carried thereby. The machine 14 is then moved forwardly (to the left of FIGURE 2) to dispose tine members 40 underneath the nearest ties 12, after which clamping devices 58 are set against the car side walls and the tie carrier frames are retracted to draw the ties 12 to the level of ejector device 42.

If the ties 12 have not yet been separated from their bundles, this may be done at this point in the handling of the ties. An employee may thus take a suitable tool

and sever the steel bands 15 that are ordinarily employed for binding the ties together in the aforesaid bundles 13.

Assuming that the ties are free from binding engagement with each other for ejection over the side of the car, and that the ejector blade 44 was initially positioned approximately above one or the other of the sides 22 of the car being unloaded (see FIGURE 5), for instance, the left hand side of the car in the showing of FIGURE 5, one of the ties will now be within operating range of the reciprocating ejector blade 44 and if this is not so, the fork lift frame 34 may be tilted in the manner indicated by the inclined broken line showing of FIGURE 1 to roll a tie 12 to this position. The rake device 56 may also be operated at this point to facilitate positioning of the ties.

Assuming that the ties are to be dropped over the right hand car side 22 in the showing of FIGURE 5, the right hand tie ejection movement control device 62 is lowered from the broken line position of FIGURE 8 to the full line position therein illustrated.

The tie unloading operation is commenced by the train including cars 10 and 10a being moved at approximately a walking speed from the beginning of the trackage being covered with a designated individual walking alongside the train and pointing out the location of ties previously marked for replacement so that ties from car 10a and subsequent cars may be dropped (while the train is moving) approximately where they are to be used. When the first tie is to be dropped, the tie ejector blade 44 is moved to the right of FIGURE 5 to push the right hand end of the tie being ejected into the device 62, which is in the form of a generally quadrilateral tube 90 having an open upper end 92, a lower open end 94 and a concave guiding surface 96 extending between the two open ends. As the tie 12 is moved to the right of FIGURE 5, it enters the open end 92 of device 62, engages guiding surface 96 (see FIGURE 8), and angles downwardly toward the ground; the ejector blade 44 is moved to the right of FIGURE 5, until the tie drops by its own weight, after which it is returned to the full line position of FIGURE 5 if all the ties are to be dropped on the right hand side of the car as shown in FIGURE 5.

As indicated in FIGURES 8 and 10, the tie movement control device 62 restrains the movement of the tie as it drops to the ground and insures that the tie will not 45 bounce and roll away from the track, but rather drop to the ground in a controlled manner and lie longitudinally of the track due to the restraining action of the device 62 on the trailing end of the tie. As the train moves during the tie unloading process, the tie will fall to the track bed somewhat as indicated in FIGURE 10.

Further ties are handled in like manner until all of the ties supported by the tie members 40 have been ejected over the side of the car.

After all of the ties carried by tie members 40 have been ejected over the side of the car, the cylinders 52 are again actuated to lower the tine members below the next adjacent ties and the tine members again elevated to ready another group of ties for ejection in a manner similar to that described above.

As forward movement of the wheeled frame 30 is required to bring the fork lift frame 34 within reach of further ties to be unloaded, the clamp devices 58 are released and the hydraulic motor 72 actuated to move the frame as required, brakes 60 being employed to stop the wheeled frame at the desired location. As soon as all of the ties of the car 10a have been unloaded, the machine 14 is moved in the direction of the adjacent car 10 and onto bridging members 28 fixed between the sides of the adjacent cars 10 and 10a and the fork lift frame 34 is inserted in the space 80 (see FIGURE 3) at the end of the car between the two vertical spacer members 12a with tine members 40 retracted to the broken line position of FIGURE 17 (and thus in the plane of the fork

lift frame 34). The hydraulic rams 52 are then operated to lower the tine carrier frames 38 until tine members 40 are below the level of the ties 12 resting on tie rows 16, after which rams 54 are operated to move the tine members 40 to the full line positions of FIGURES 17 and 18, which disposes them underneath the adjacent ties 12, after which rams 52 may be operated to draw the ties adjacent spacer members 12a to the elevation of the ejector device 42 for ejection in the manner already described. Further unloading of ties proceeds until the first car 10 is empty, after which the wheeled frame 30 is driven over similar bridge members 28 applied between adjacent cars 10 as unloading of the respective cars proceeds to the point where such a crossing is necessary. 15 This procedure continues until all the new ties required have been ejected from the train.

When the tie unloading operation is completed, machine 14 is driven back to its initial position on car 10a and again made fast thereto for transit to another unloading site or to a creosoting plant for another load of ties. Since fork lift frame 34 may be moved to the horizontal position shown in phantom in FIGURE 1 and tine members 40 retracted to the broken position of FIGURE 17, machine 14 is disposed well within permissible heights permitted railroad cars.

Our tie unloader device is preferably arranged to drop the ties alongside the track approximately 8 feet from the center line of the track and in the longitudinally extending position already mentioned; since tie renewals are most frequently required at the rail joints, ties will be unloaded at least about every 19 feet along the right of way, but frequently more extensive replacements will be made and our machine satisfies this requirement with facility. We contemplate that the rated unloading rate of machine 14 will be from 6 to 10 ties per minute but the actual unloading rate employed will depend on the spacing between ties that are to be renewed. Preferably, the two wheels marked 32a are slidably connected to the wheeled frame (see FIGURES 5 and 9) to permit the wheels to follow the bowing out (if any) of the top of the gondola sides as the unloader machine 14 is moved along the car 10 being unloaded.

SPECIFIC DESCRIPTION

The cars 10 and 10a employed in practicing our method and system may be any conventional make of gondola car, the structural features of which are well known in the art; the showing of the various drawing figures is intended to represent any conventional make of gondola car, though it may be pointed out that the car side walls 22 are customarily capped by a rim member 100, which forms an adequate track for the wheels 32 and 32a of our device. Gondola cars also customarily include the reinforcing members 102 that are disposed in spaced relation along the outside of the top of the individual car sides, and the spaces 103 between them thus form a convenient grip for the clamp devices 58 (see FIGURE 9). As is well known in the art, all gondola cars have some structure along the tops and the side walls equivalent to that illustrated.

The car side walls 22 are only diagrammatically illustrated and may be of a type found in any gondola car, though they may also be provided with a wood lining 104 along the inside of the car. Similar remarks apply to 65 the other car structure illustrated.

The bridging members 28 may be in the form of elongate bars 106 having a channel-shaped cross section, with the bars 106 fixed between adjacent respective side walls 22 of adjacent cars in any convenient manner, such as by 70 suitable clamps or bolts.

The wheeled frame 30 of machine 14 may be of any suitable type, though the illustrated embodiment contemplates an arrangement including the spaced longitudinally extending members 110 (see FIGURE 5) joined together at their ends by transversely extending members

112, with the inner frame members 110 being braced by transversely extending member 114. The forward wheels 32 and 32a are keyed to a common shaft 116 that is rotatably mounted in suitable plain bearings (not shown) secured to the wheeled frame in any convenient manner that will prevent twisting of the shaft 116. The rearward wheels 32 and 32a are keyed to individual shafts 117 rotatably secured to the frame in like manner. The shaft 116 and the shaft 117 mounting a wheel 32a are splined or grooved where indicated at 118, with the wheels 32a being complementarily formed to provide the aforementioned sliding keying relation between these wheels and the respective shafts. The shaft 116 and the splined shaft 117 may be provided with suitable pins 120 to retain the wheels 32a in place. The wheels of frame 30 thus have a variable gauge to follow the contour of the car side walls 22, which in some cases may vary considerably, depending on the condition of the car.

The operator's seat, the internal combustion engine 66, the pump 68, the reservoir 70, the hydraulic motor 72 and other supplementary equipment may be arranged upon and around the frame 30 as may be necessary or desirable.

The guideways 36 of the fork lift frame 34 are defined by channel members 122 arranged in back to back pairs (see FIGURE 5). Cylinder 52 of each guideway is secured between the respective pairs of channel members 122 by a suitable pin 124 at the tops of the respective guideways 36.

In the area of the ejector device 42, the channel-shaped members are joined together by median channel members 126 (see FIGURES 5 and 6) and projecting laterally of each guideway, are the like horizontally disposed end channel members 128, with the channel members 126 and 128 being joined together by elongate plates 130 (see FIGURES 4-7). The channel members 122 are preferably joined adjacent the top of the respective guideways 36 by brace plate 132. Ram 50 in the arrangement illustrated is pivoted to one of the guideways 36, as by employing the bracket structure diagrammatically illustrated at 134, the ram being pivotally mounted on a suitable support 135 that is secured to frame 30 in any suitable manner, as by welding. Of course, the ram 50 may be positioned transversely of the car as seems necessary or desirable to accommodate the equipment that is to be carried by the wheeled frame as well as the driver's seat and still permit the swinging action of the fork lift frame that is desired.

The fork lift frame 34 is pivoted to the wheeled frame 30 by pivot plates 138 affixed to the outer of the channel members 122 of each guideway 36 and journaled on shaft 116 by suitable plain bearings 140. Plates 138 should be of sufficient length that frame 34 may be horizontally disposed when machine is not in use or when it is to be moved from one car to another.

The structural features of the tine carrier frames 38 are best illustrated in FIGURES 11-16 and it will be noted that they each comprise in the illustrated embodiment spaced channel members 144 joined together by spacer plates 146 all welded together to form a rigid unit. Wear plates 148 are preferably affixed to the corners of the channel members 144 somewhat as indicated in FIGURE 15 and are suitably proportioned to insure the desired movement of the tine carrier frames within the respective guideways 36.

Each of the tine carrier frames at their lower ends has affixed thereto a fabricated tine pivot structure 150 (see FIGURES 14 and 16) defined by plates 152, 153, 154 and 155, which are welded to the lower ends of the channel members 144 at the upper ends of the former, and are welded together by the spaced web plates 156 and 157 indicated in FIGURE 12. The plates 156 and 157 are formed with appropriate holes 158 to receive the piston rod 160 of the respective hydraulic cylinders 52,

which rods may be affixed in place by employing appropriate nuts 162.

The plates 152-155 are slotted as indicated as 164, 166, 168 and 170 in FIGURE 14 to accommodate the movement of the tine member 40 indicated in FIGURES 18 and 19, and it will thus be seen that slots 164 and 166 merge together to form a single opening, as do slots 168 and 170.

The individual tine members are shaped as required to best support the ties to be lifted and are formed with appropriate holes 172 to receive the respective piston rods 169 of rams 52. Members 40 thus comprise a forwardly extending tine or prong portion 174 and a rearwardly extending crank arm 176 which in accordance with the present invention has affixed thereto a lug 178 that is disposed at right angles to the respective tine members 40 and is pivotally connected at its projecting end 179 to the piston rod 180 of the respective rams 54. Rams 54 are carried by the tine support frames by being pivoted between spaced carrier plates 182, which are affixed to a channel member 184 that is in turn welded to the tine pivot structures 150 of the respective tine carrier frames. Channel members 184 may be braced by appropriate webs 186.

The tie ejector paddle or blade 44 in the illustrated embodiment is composed of two angle members 190 (see FIGURE 5) having their flanges 192 fixed together in any suitable manner to define the outwardly projecting blade portion 193 and having their flanges 194 (see FIGURE 4) received in a guideway 196 defined by the adjacent plate 139 and upper and lower guide bars 197 and 198, which are respectively provided with lips 199 to properly restrain the ejector blade from movement out of the guideway 196.

The ejector blade 44 in the illustrated embodiment is affixed to the flexible endless member 200 which in the form illustrated is a chain 202 trained over end sprockets 203 and 204 affixed to the respective stub shafts 206 and 208 that are journaled by the respective spaced pairs of channel members 128. As indicated in FIGURES 5 and 6, the chain 202 is also trained over a sprocket 210 which is keyed to a shaft 212 that is journaled between space plates 214 and 216 affixed to the respective channel members 126, which shaft 212 also has keyed thereto a pinion 218 that meshes with a rack member 220 connected to the piston rod 222 of a hydraulic ram 224 carried by the fork lift frame 34 as by being pivoted between a plate 226 affixed to the upper channel member 128 at the left hand side of the machine as shown in FIGURE 5 and an angle member 228 are fixed immediately below the plate 226.

Of course, when the ram 224 is reciprocated, rack member 220 engages pinion 218 to turn the sprocket 210, which effects actuation of endless member 200 and the consequent member movement of ejector blade 44. The gearing and chain training arrangement should be such that the ejector blade 44 can be moved between the sides 22 of the car as the ram 224 is operated between its extreme extended and contracted positions.

The tie ejection movement control devices 62 are swingably secured to either side of the fork lift frame for movement between the upper retracted position of FIGURE 8 and the lower operative position indicated by the same figure. The quadrilateral tubular member 90 preferably has affixed thereto as by welding a round bar 230 which is received in a sleeve 232 welded to the spaced upright channel members 234 that are affixed to the respective pairs of plates 130 at either end of the frame 34. The tube 90 comprises forward and rearward planar walls 236, the planar side wall 238 and the arcuate wall 239 which defines the concave guiding surface 96, all rigidly connected together in any convenient manner, as by welding. The wall 238 is adapted to bear against the respective forward channel members 234 and angle members 241 bear against the respective rearward channel members 234,

in the lower operative position of devices 62 (see FIGURES 5 and 8.)

As indicated in FIGURE 10, the rearward wall 236 of devices 62 terminates above the bottom periphery 240 of tubular member 90 to define an opening 242 that accommodates the angulation of the tie which will occur after the tie has dropped to the ground while machine 14 is being moved in a forward direction.

It will thus be seen that the devices 62 not only guide the tie as it drops to the ground, but exercise a restraining action on the upper end of the tie which prohibits the tie from rolling uncontrollably down an embankment or away from the track.

The clamp devices 58 in the form illustrated comprise an arm 350 formed with a hooked end 252 and pivoted as at 254 to a suitable support structure 256 affixed in any suitable manner to the wheeled frame 30. The individual arms 250 may be actuated by appropriate hydraulic rams 258, which may be secured to the respective arms in a manner diagrammatically indicated at 260.

The brake devices 60 may be more or less conventional and include a suitable operating lever 262 pivoted to the wheeled frame as at 264 and operatively connected to brake shoes 266 by appropriate links 268 and 270.

Rake device 56 comprises ram 280 having its piston rod affixed to rake head 282 to define rake member 57. Ram 56 is pivotally connected to one of the guideways 36 as at 284 and is moved about the axis of pivot 284 by ram 286 pivotally connected to said guideway 36 as at 288 and including a piston rod 290 pivotally connected to ram 280 as at 292. The shaft 116 may be rotated to drive the wheeled frame longitudinally of the car as by employing an appropriate chain 272 trained over sprockets 274 and 276, the latter being actuated by hydraulic motor 72 in any suitable manner.

Of course, the hydraulic rams or cylinders illustrated may be operatively connected into a hydraulic system in any conventional manner, and preferably all hydraulic cylinders are double acting. The hydraulic system and apparatus employed should be such that rams or hydraulic cylinders illustrated will move the components they are associated with under fully loaded conditions, or restrain them from movement, as may be necessary during operation of machine 14. Motor 66 may be any type of prime mover.

Distinguishing Characteristics of the Invention

It will therefore be seen that our invention provides a number of important advantages in the art of handling track ties. For instance, the cars used to transport the ties may be equipment that is in such bad shape that it cannot be used for any other purpose. Since the gauge of the frame wheels of machine 14 is adapted to adjust itself to the configuration of the gondola car side walls, any deformation of such side walls within reasonable limits will not affect the operation of our machine or method.

Furthermore, at the creosoting plant, the loading operation may be substantially mechanized, the only hand loading required being in the positioning of the ties 12a and those forming the support rows 16. The ties thus may be taken as they come from the creosoting tanks and loaded by appropriate mechanized devices directly into the gondola cars that are to carry the ties to the point of intended use. Manifestly, this eliminates the costly tie loading methods heretofore employed at the creosoting plants and the resulting costly and arduous tie unloading operation required at the point of use.

Furthermore, our tie unloading machine may be employed on all gondola cars used in practicing our method which means that one machine may be used to unload an entire train of gondola cars. It will thus be appreciated that the capital investment required to practice our invention is held to the cost of the machine 14 and whatever tie down devices may be required to make same fast to a car 10a during transit.

For convenience, ties 12a and those forming rows 16 may be permanently affixed to the individual cars in which they are employed, but in any event, they form supports and spacers for ties 12 and are so referred to in some of the appended claims. Of course, ties 12a and those forming rows 16 are spaced apart to receive the fork lift frame 34 and its tine members 40.

The foregoing description and the drawings are given merely to explain and illustrate our invention and the invention is not to be limited thereto, except insofar as the appended claims are so limited, since those skilled in the art who have our disclosure before them will be able to make modifications and variations therein without departing from the scope of the invention.

We claim:

1. Apparatus for unloading railroad track ties from gondola cars comprising a frame provided with wheels adapted to ride on the side walls of a gondola car, a fork lift structure carried by said frame and including a plurality of reciprocably mounted tine structures each mounted in a guideway and provided with a tine member, means for reciprocating said tine structures, said tine members each being mounted for swinging movement between substantially parallel positions and positions wherein they are in alignment with each other, and a tie ejector mechanism carried by said fork lift structure and including means for sliding ties carried by said tine members, when in their first mentioned positions, from said tine members over the side of the car.

2. Apparatus for unloading track ties from gondola cars having a loading arrangement in which the ties extend crosswise of the car and rest on spaced supports that extend longitudinally of the car and at one end of the car the ties bear against spaced vertically disposed supports that are interposed between the ties and the end of the car, said apparatus comprising a wheeled frame adapted to ride on the sides of the car, said frame carrying a fork lift structure including spaced coplanar parallel guideways, a tine carrier frame reciprocably mounted in each of said guideways, said guideways being fixed together and secured to said wheeled frame to define a fork lift frame that is disposed transversely of the car when the wheeled frame rests on the car side walls, said fork lift frame being secured to said wheeled frame for swinging movement about a substantially horizontal axis, means carried by said fork lift frame for reciprocating said tine carrier frames, each of said tine carrier frames carrying a tine member mounted for pivotal movement about an axis extending longitudinally of the respective guideways, and means for swinging said tine members about said axes thereof between positions in alignment with the plane of said fork lift frame to positions disposed normally of said plane and extending in the same direction from said plane, said fork lift frame being proportioned for insertion between the ties and the vertically disposed supports at the end of the car, whereby when said tine members are disposed in alignment with said plane of said fork lift frame, said fork lift frame may be inserted between said ties and the vertically disposed supports at the end of the car, to permit said tine carrier frames to be lowered to dispose said tine members below said ties, whereupon said tine members may be moved to their last mentioned positions and said tine carrier frames elevated to commence lifting the ties above the level of the car side walls, and means carried by said fork lift frame for sliding the ties over the side of the car.

3. Apparatus for unloading track ties from gondola cars having a loading arrangement in which the ties extend crosswise of the car and rest on spaced supports that extend longitudinally of the car and at one end of the car the ties bear against spaced vertically disposed supports that are interposed between the ties and the end of the car, said apparatus comprising a wheeled frame adapted to ride on the tops of the sides of the car, said frame carrying a fork lift structure including spaced coplanar

11

parallel guideways, a tine carrier frame reciprocably mounted in each of said guideways, said guideways being fixed together and secured to said wheeled frame to define a fork lift frame that is disposed transversely of the car when the wheeled frame rests on the car side walls, said fork lift frame being secured to said wheeled frame for swinging movement about a substantially horizontal axis, power means for swinging said fork lift frame about said horizontal axis and for maintaining said fork lift frame against such swinging movement, power means carried by said fork lift frame for reciprocating said tine carrier frames, each of said tine carrier frames carrying a tine member mounted for pivotal movement about an axis extending longitudinally of the respective guideways, power means carried by said fork lift frame for swinging said tine members about said axes thereof between positions in alignment with the plane of said fork lift frame to positions disposed normally of said plane and extending in the same direction from said plane and away from said wheeled frame, said fork lift frame being proportioned for insertion between the ties and the vertically disposed supports at the end of the car whereby when said tine members are disposed in alignment with said plane of said fork lift frame, said fork lift frame may be inserted between said ties and the vertically disposed supports at the end of the car, to permit said tine carrier frames to be lowered to dispose said tine members below said ties, whereupon said tine members may be moved to their last mentioned positions and said tine carrier frames elevated to commence lifting the ties above the level of the car side walls, and power means carried by said fork lift frame for sliding the ties over the side of the car after the ties have been lifted above the side of the car.

4. The apparatus set forth in claim 3 wherein the wheels of said wheeled frame are double flanged, and including means for journalling said wheels on said frame for permitting said wheels to follow the lateral contour of the respective tops of the car side walls when the apparatus is in operative position on the car.

5. The apparatus set forth in claim 3 wherein said fork lift frame has secured thereto above the last mentioned power means a rake device including a retractable and extensible rake element that projects over the ties when said apparatus is in operative position on the car, said device being mounted for swinging movement about a substantially horizontal axis, and including power means for raising and lowering said rake device about said horizontal axis.

6. The apparatus set forth in claim 3 wherein the last mentioned power means comprises a tie ejector guideway affixed to said fork lift frame normally of the first mentioned guideways, said tie ejector guideway having a length that exceeds the length of the ties adapted to be employed in said loading arrangement, said tie ejector guideway being centered on said fork lift frame, a tie ejector blade slidably mounted in said tie ejector guideway for movement over substantially the length of the latter, said tie ejector blade projecting normally of said plane of said fork lift frame and away from said wheeled frame, and power means for moving said blade longitudinally of said tie ejector guideway.

7. The apparatus set forth in claim 6 wherein said fork lift frame carries at one side thereof a tie chute structure, said chute structure comprising a tubular member having one of its open ends secured to said fork lift frame for alignment with the path of movement of said tie ejector blade and the other of its ends adapted to depend from said fork lift frame, said tubular member including an inner concave camming surface opposing said one end thereof and leading to said other end thereof, whereby a tie moved over the side of the car by said ejector blade has a controlled drop to the track bed through said tubular member.

12

8. The apparatus set forth in claim 3 including a clamping arm pivotally secured to either side of said wheeled frame and having one end thereof proportioned to engage against the respective sides of the car, and power means for pressing said one end of said arms into engagement with the respective sides, whereby said wheeled frame may be clamped to the car during operation of said apparatus.

9. The apparatus set forth in claim 3 wherein said tine carrier frame guideways each comprise spaced elongate members secured together in parallel relation, and wherein said tine carrier frames each comprise spaced elongate members secured together in parallel relation and slidably mounted within the respective tine carrier frame guideways, with the power means for reciprocating said tine carrier frames each comprising a ram secured within the upper ends of the respective tine carrier frame guideways and including a piston rod affixed to the respective carrier frames.

10. The apparatus set forth in claim 3 wherein said tine carrier frames each include a laterally directed arm affixed to the lower end thereof and in alignment with the plane of said fork lift frame, and a ram connected between said arm and the tine of the respective carrier frames, said rams forming said power means for swinging said tine members.

11. Apparatus for unloading railroad track ties from gondola cars comprising a vehicle including wheel means for mounting the vehicle on top of the side walls of a gondola car for movement longitudinally of the car, fork lift means carried by said vehicle for lifting ties above the top of the car side walls and including a plurality of spaced tine members mounted for reciprocable movement between positions adjacent the vehicle and positions adjacent the floor of the car when the vehicle is on the car and said fork lift means is in operative position with respect thereto, means for selectively reciprocating said tine members between said positions, said tine members each being mounted for swinging movement between substantially parallel positions and positions wherein they are in substantial alignment, and a tie ejector mechanism carried by said vehicle and including tie ejecting means for moving, longitudinally thereof and over the top of one side wall of the car, ties carried by said tine members when such ties have been raised above the top of said car side walls.

12. The apparatus set forth in claim 1 wherein said tine members are mounted in a guideway structure that is pivotally connected to the said vehicle adjacent one end thereof for movement between a substantially vertical operative position and a substantially horizontal inoperative position overlying the vehicle.

13. The apparatus set forth in claim 1 wherein said vehicle carries at one side thereof a tie chute structure, said chute structure comprising a tubular member having one of its open ends secured to said vehicle for alignment with the path of movement of ties when ejected by said tie ejector means and the other of its ends adapted to depend from said vehicle, said tubular member including an inner concave camming surface opposing said one end thereof and leading to said other end thereof, whereby a tie moved over the side of the car by said ejector mechanism has a controlled drop to the track bed through said tubular member.

14. The method of loading and unloading railroad ties from a gondola car of the type comprising fixed side and end walls, which method includes forming at least two spaced rows of ties in end to end relation along the floor of the car substantially between the ends thereof, placing at least two ties against one end of the car in an upstanding spaced relation, filling the car with ties by placing same in the car crosswise of said rows of ties, transporting the car to the destination of the ties, and unloading the ties by inserting a tie lifting tool from the

top of the car down into the space between the said two ties at said one end of the car and under adjacent crosswise extending ties, lifting such ties above the top of the side walls of the car, consecutively ejecting such ties one by one over the top of one side wall of the car by moving the individual ties lengthwise thereof, and removing further ties as required by inserting the tool from the top of the car under the next adjacent of said crosswise extending ties and lifting such ties above the side walls of the car for sequential ejection over said one side wall in like manner.

15. The method set forth in claim 14 including guiding the movement of the individual ejected ties as they fall to the ground so that they engage the ground in a substantially vertical position

16. The method set forth in claim 15 wherein the car is moved at walking speed at the ties are being ejected from the car.

UNITED STATES PATENT OFFICE
CERTIFICATE OF CORRECTION

October 22, 1963

Patent No. 3,107,803

Virgil E. Glosup et al.

It is hereby certified that error appears in the above numbered patent requiring correction and that the said Letters Patent should read as corrected below.

Column 12, lines 47 and 53, for the claim reference numeral "1", each occurrence, read -- 11 --; column 13, line 18, for "at", second occurrence, read -- as --.

Signed and sealed this 21st day of April 1964.
